Inventor:

Jason I. Irving

By Smith & O'Brien
Attest.

UNITED STATES PATENT OFFICE.

JASON I. IRVING, OF SAN FRANCISCO, CALIFORNIA.

STATION-INDICATOR.

SPECIFICATION forming part of Letters Patent No. 393,706, dated November 27, 1888.

Application filed February 27, 1888. Serial No. 265,509. (No model.)

To all whom it may concern:

Be it known that I, JASON I. IRVING, a citizen of the United States, residing in the city and county of San Francisco, in the State of California, have invented certain new and useful Improvements in Station-Indicators for Railway-Cars; and I do hereby declare that the following is a full, clear, and exact description of my said invention, reference being had to the drawings that form part of this specification.

My invention relates to improvements in street or station indicators for railway-cars, and it embraces a certain novel construction and combination of parts and mechanism, as hereinafter fully described, and the production of an indicator that is capable of containing a considerable number of name-bearing cards or plates in small compass and of exposing to view both sides of each plate in such manner that the two surfaces of a plate can be utilized, if desired. In addition to this my improvements have for their object to simplify the operating mechanism of such indicator-boxes.

The following description explains the nature of these improvements and the manner in which I have constructed, combined, and applied the same in carrying out my invention, the accompanying drawings being referred to by figures and letters.

In the said drawings, Figure 1 represents a front view of the indicator complete. Fig. 2 is a sectional view taken transversely through the case or box at the vertical line X X, Fig. 1. Fig. 3 is a similar section taken at the line Y Y, Fig. 1. Fig. 4 is a longitudinal section taken horizontally through the box at the line Z Z, Fig. 3. Fig. 5 shows one of the plates detached from the drum or carrying-cylinder, and Fig. 6 is a longitudinal section taken through the middle of the cylinder. Figs. 7 and 7^a are inside and outside views, respectively, of the sliding boxes that carry the journals of the cylinder; and Fig. 7^b is a cross-section through Fig. 7, taken at the line X Y, Fig. 7^a. Fig. 8 represents the lever and dog that rotate the cylinder.

Similar letters of reference indicate the same parts in all the figures of the drawings.

A represents a suitable case or box, the dimensions of which are proportioned to the

length and breadth of the cards or plates that carry the names or matter to be displayed, so that the opening in the front of the box shall be of suitable size to expose to view the faces of two plates, one above the other, the axis of the cylinder that carries the plates being set about midway of the opening. The width of the opening is somewhat greater than the length of the plate to allow the plates to drop forward and turn on their hinges by gravity.

B B are the plates, and C C^x C^y D the parts composing the drum or cylinder to which the plates are attached by hinge-joints at one side and in such manner that the other ends of the plates are left free to be acted upon by the rotation of the cylinder and the force of gravity.

C C^x are two cylindrical heads fixed on a shaft, D, at the ends thereof, but leaving suitable journal portions beyond; and C^y is a similar head fixed on the shaft about midway between the others.

E E are wires or rods of small diameter set in close and parallel order through holes in the heads and fitted loosely in place, so that they can be drawn out. They are arranged to be drawn out from the right-hand end of the cylinder, and to prevent them from working out of the left-hand head a cap, D^x, with a recess of suitable diameter to take in the head, is slipped on the end of the shaft. The rods take through knuckles B^x B^y on the plates B and form pintles for the plates to turn on.

The front of the cylinder is set about in line with or is tangent to the back line of the case-opening, and in such position also with respect to the top edge of the opening that the distance vertically from the rim of the cylinder, where the horizontal diameter, if drawn, would pass through it, to the edge a' of the opening is somewhat less than the distance from the hinge standing on that line up to the top edge of the plate, so that the edge of the case-opening shall act as a stop to hold the plate standing in such position and prevent it from falling forward. The relative position of these parts is seen in Fig. 2. It will be noticed that the plate thus standing at the opening is thrown slightly forward at the top. This is done to keep the plate upright during its exposure, and to prevent it from being thrown backward by the motions or jar of the car during its travel.

Rotation of the cylinder in a forward direction has the effect to draw down the plate until its top edge clears the edge of the opening, when the released plate will drop forward and 5 turn over by gravity. In this movement the plate is reversed or its other surface is presented to the front and is exposed to view through that portion of the opening below the center. The length of each rotative movement 10 of the cylinder is sufficient to release the front or leading plate of those above the axis, but not to let more than one plate at a time drop forward through the opening. Such movement of the cylinder is produced by a vibrating 15 dog, G, and ratchet-teeth H, which are formed for the purpose on the rim of the head C^x. The dog is loosely pivoted on the end of a lever, I, and works loosely through a staple, K, on the inner side of the case, as shown in 20 Fig. 3 of the drawings. The locking-pawl L is placed over the cylinder to prevent backward motion, as the greater weight is on the rear side of the axis.

The lever I is pivoted in the bracket M on 25 the outside of the case, and its outer end is suitably connected to a hand-lever or an operating-rod, if the indicator is intended to be worked by hand, or to the automatic mechanism which may be employed to work it. The 30 upstroke of the outer end of the lever turns the cylinder the distance of one tooth, and this movement is sufficient to release the edge of the foremost plate from the top edge of the opening.

35 The sliding journal-boxes P are let into the front of the case at the side of the opening, and are readily drawn out to remove the cylinder for purposes of cleaning or repairing or to change or adjust the plates.

The box has a dovetail rib, P^x, that slides 40 into a groove of corresponding form in the case, and also a hole, P^y, to take the end of the shaft D. By drawing out both boxes from the grooves all the parts with the exception of the vibrating dog are easily removed from the case. 45

The boxes are held in place by the hooks R and pins or hasps on the sides of the case. These form a simple means for holding the boxes; but other locking devices could be used in their place.

50 As thus constructed and operated, it will be seen that a considerable number of cards or plates can be arranged in close compact manner, so that a case of comparatively small size will contain a large number of signs or name-bearing plates; also, that both faces of the plates can be utilized. In such case two plates are shown at the same time through the opening, and while one displays the name of the street or station the other plate can be used to 55 display additional names or other matter for the benefit or instruction of passengers.

Having thus fully described my invention, what I claim, and desire to secure by Letters Patent, is—

60 In combination, the case A, having grooves for the sliding boxes P P, the boxes P, removable from the front thereof and having bearings for the journals of the cylinder, and an opening in the case-front of suitable size to 65 allow the cylinder to be withdrawn from the case, substantially as described.

In testimony that I claim the foregoing I have hereunto set my hand and seal.

JASON I. IRVING. [L. s.]
